RUDOLPH S. WEINER, OF EL PASO, TEXAS, ASSIGNOR TO SULLIVAN MACHINERY COMPANY, OF CLAREMONT, NEW HAMPSHIRE, A CORPORATION OF MASSACHUSETTS.

DRILL-BIT-RETAINING DEVICE.

1,164,560.

Specification of Letters Patent. Patented Dec. 14, 1915.

Application filed June 5, 1914. Serial No. 843,284.

To all whom it may concern:

Be it known that I, RUDOLPH S. WEINER, a citizen of the United States, and a resident of El Paso, county of El Paso, State of Texas, (whose post-office address is El Paso, Texas,) have invented an Improvement in Drill-Bit-Retaining Devices, of which the following description, in connection with the accompanying drawings, is a specification, like characters on the drawings representing like parts.

This invention relates to drill bit retaining devices for drills of the hammer type, and more particularly, though not exclusively, to such devices as apply to fluid pressure tools of the piston hammer type in which the drill bit is struck a hammer blow tending to drive it out of the drill chuck when the bit is not resting against its work.

The invention will be best understood by reference to the following description when taken in connection with the accompanying illustration of one specific embodiment thereof, while its scope will be more particularly pointed out in the appended claims.

In the drawings: Figure 1 is a plan partly in central, longitudinal section showing the forward end of a pressure-fluid rock drill of the piston hammer type to which there is applied one form of the invention; Fig. 2 is a side elevation of the parts represented in Fig. 1; Fig. 3 is a view similar to Fig. 1 showing a modified form of the invention; and Fig. 4 is a view similar to Fig. 2 showing the same modification in side elevation.

Referring to the drawings and to the embodiment of the invention selected for illustration, I have there shown a fluid-pressure rock drill of the piston hammer type having a cylinder 1 in which operates the piston 2 having the reduced forward extension 3 constituting a hammer adapted to deliver blows upon the inner end or head 4 of the drill bit. 5. The drill bit head 4 is loosely held in the drill chuck 6 so as to have free, longitudinal movement therein, but is preferably of non-circular cross section conforming to the non-circular cross section of the chuck so as to be non-rotatable with relation thereto. The chuck is herein rotatably mounted in an elongated front cylinder head 7, preferably supported in a yielding manner at the for-

ward end of the cylinder. To this end the cylinder head is provided with laterally projecting lugs 8 through which extend a pair of tie rods 9. The rear ends of these rods extend through the lugs 8 and are secured to the rear end of the cylinder or to the rear cylinder head (not shown) in the usual manner. The forward portions of the rods are encircled by cushioning springs 10 interposed between the lugs 8 and suitable abutments carried by the rods, such as the nuts 11 threaded on to their front ends. The arrangement is such that the front cylinder head is yieldingly mounted on the cylinder so as to cushion the blow of the piston should the latter strike the head or the parts sustained thereby.

The parts so far described are of usual, conventional construction and require no further description.

Referring now more specifically to the novel features of the invention, the drill bit 5 is provided with an enlarged portion or abutment 12 between the shank 5 or main portion of the bit and the head 4. This enlargement is shouldered to engage the forward end of the drill chuck and limit the inward movement of the drill bit as it rebounds after being struck by the piston hammer. It also serves in coöperation with a stop or retaining device both to arrest the forward movement of the drill bit when struck by the piston hammer and to cause the drill bit to be withdrawn with the tool from the work if it has any tendency to stick in the drill hole. To this end there is provided a retaining or stopping device 80 in the form of a chain 13 or other flexible member adapted to engage the drill bit shank as by encircling the same in front of the enlargement 12 and adapted to have its ends attached to some part of the drill. 90 Preferably, as herein, the ends of the flexible retaining member are attached to the forward cylinder head and preferably also they are secured thereto by some kind of a yielding attachment. Herein, for such purpose the opposite ends of the chain are each attached to an eye 14 formed in the forward end of a link 15, the opposite end of the link being shaped in the form of a sleeve 16 which encircles the tie rod 9 between the lug 8 and the cushioning spring 10. Any

downward pull upon the chain, therefore, is transmitted through the links to the cushioning springs 10 and as the latter compress under such pull the link sleeves 16 are 5 adapted to have the necessary play or sliding movement upon the tie rods 9. To assist in guiding the links to move in a parallel direction, their forward ends are guided between fixed lugs 17 carried by ribs 18 on the 10 sides of the front cylinder head. The chain 13 intermediate the eyes 14 forms a loop which is of such length that the drill bit when first inserted in the chuck may have its head inserted through a twist or hitch in 15 the loop, forming one or more coils 19 thereabout, so that when the drill bit is in place the coil may be slipped down into some such position as represented and may be drawn taut in the form of a tight hitch about the 20 shank of the bit. The loop also is of such length that this brings the hitch sufficiently 25 near the enlargement 12 to prevent the drill head from accidentally withdrawing from the chuck. If the hammer strikes the drill bit head with the bit withdrawn from the work and tends to drive the bit forward, or if the bit sticks in the drill hole when the machine is withdrawn from the work, the 30 enlargement 12 slips forward until it strikes the hitch, when it is tightly gripped by the chain. Further forward movement is prevented, any tendency to advance merely causing the chain to grip the shank still 35 tighter. On the other hand, the drill shank 40 may be readily removed by the operative by simply slipping the hitch up the shank toward the chuck, whereat the coil 19 may be easily opened to allow the withdrawal of the enlargement 12 in the drill bit head therethrough. It will be seen that the forward movement of the drill bit, which this device is designed to limit, tends to tighten 45 the hitch about the shank and initiates the direct opposite of the conditions required for releasing the drill bit. Furthermore, in 50 the case of a holder of the chain type, the links of the chain when engaged by the enlargement 12 exert a gripping or pinching action which effectively arrests any tendency of the shank to slip through the hitch.

In operation the springs 10 serve to cushion the cylinder head should the piston strike the same, and they also serve to cushion the stopping or retaining effect of the 55 hitch or coil 19 on the abutment 12 when the latter is driven forward by the piston striking the drill bit head with the drill bit removed from the work.

In Figs. 2 and 3 I have shown a modified 60 form of the invention wherein for the chain 13 I have substituted a short section 20 of wire rope or cable. The end of the cable is formed into an eye 21 which is secured to the eye 22 formed in a lug on the side of the sleeve 23, the latter encircling the side

rod 9 between the lug 8 and the cushioning spring 10. The sleeve is carried down at 24 to form an inclosing barrel about the spring. At the forward end of the cylinder head the loop member 20 is preferably 70 guided through an eye in the lug 25 projecting from the side of the head. The cable member 20 provides a loop which is used in the same way as has been described with reference to the chain member 12. Both the 75 cable 20 and chain 12 form ligatures between the bit and the machine that might be described as funicular, that is, they have the limberness of a cord and do not have any inherent shape such as a bar of metal or 80 the like would have. It is obvious that flexible retaining members of other forms and secured to the drilling machine in other ways than those herein indicated may be employed.

While I have herein shown and described one specific embodiment of the invention for illustrative purposes and have disclosed and discussed in detail the construction and arrangement incidental to one specific application thereof, it is to be understood that the invention is not limited to the details or relative arrangement of parts nor to the specific embodiment herein shown, but that extensive deviations from the illustrated 95 form of the invention may be had without departing from the principles thereof.

Claims:

1. In a hammer drill, the combination with a cylinder, a front head having lateral 100 lugs, side rods employed to clamp the front head in position and passing through the said lugs, said side rods being provided with end abutments, cushioning springs interposed between the lugs and the abutments on the side rods, a piston hammer, a drill chuck, a drill bit adapted to have longitudinal movement in said chuck and having an abutment or enlargement in front of the chuck, and a retaining device for said drill 110 bit comprising a flexible chain adapted to be wrapped or hitched about the drill bit in front of said abutment and to have its ends secured to such drilling machine, means for securing the ends of the chain to the 115 drilling machine consisting of links having each an eye at one end engaging the end of the chain, a sleeve member at the opposite end interposed between a cushioning spring and a cylinder head lug upon a side rod, and 120 means upon the cylinder head for guiding the forward end of each link.

2. In a hammer drill, the combination with a cylinder, a front head having provision to receive the cylinder side rods, side 125 rods for clamping the front head into position, cushioning springs encircling the side rods and interposed between end abutments thereon and the front head, a piston hammer, a drill chuck, a drill bit having longi- 130

tudinal movement of said chuck and provided with an enlargement in front of said chuck, and a retaining device for said drill bit comprising a flexible member adapted to be wrapped about the shank of the bit in front of said abutment, and slideable sleeves mounted upon the side rods between the cushioning springs and the cylinder head to which the ends of the flexible member

10 are secured.

3. In a hammer drill, the combination with a cylinder having a front head with side rods and cushioning springs, a drill bit adapted to have longitudinal movement in the front head, and provided with an enlargement or abutment, a drill bit retaining device comprising a flexible member adapted to be wrapped about said bit in front of said enlargement, and means interposed between the cushioning springs and the cylinder head for yieldably fastening the ends of said flexible member.

4. In a hammer drill, the combination with a cylinder, a chuck, a drill bit loosely held in said chuck for longitudinal movement, said drill bit having an enlargement and a flexible retaining member having its ends each secured to the drilling machine and having its intermediate portion forming a loop adapted to be wrapped about the shank of said drill in front of said abutment and to prevent the escape of the drill from the drilling machine.

5. In a hammer drill, the combination with a cylinder, a chuck, a drill bit loosely held in said chuck for longitudinal movement, said drill bit having an enlargement and a flexible retaining member having its ends yieldably secured to the drilling machine and having its intermediate portion forming a loop adapted to be wrapped about the shank of said drill in front of said abutment and to prevent the escape of the drill from the drilling machine.

45 6. In a hammer drill, the combination with a cylinder, a chuck, a drill bit loosely held for longitudinal movement in said chuck, said bit having an enlarged portion and a flexible retaining device comprising a member adapted to be wrapped about the drill bit shank in front of said enlarged portion, and means for securing its ends to the drilling machine.

7. In a hammer drill, the combination with a cylinder having drill bit holding means in which the bit is capable of longitudinal movement, a drill bit having an enlargement and a flexible holder having its ends attached to the drilling machine and having its intermediate portion forming a loop of sufficient length to be hitched about the shank of the bit and hold the same against escape.

8. In a hammer drill, the combination with a cylinder having drill bit holding means in

which the bit is capable of longitudinal movement, a drill bit having an enlargement and a flexible holder having its ends yieldably attached to the drilling machine and having its intermediate portion forming a loop of sufficient length to be hitched about the shank of the bit and hold the same against escape.

9. In a hammer drill, the combination with a cylinder, drill bit holding means, a drill bit longitudinally movable therein and having an enlarged portion, a flexible holding chain adapted to engage the drill bit shank in front of said enlarged portion and prevent the escape of the bit from the holding means, and means for fastening the ends of the holding chain to the drilling machine.

10. In a hammer drill, the combination with a cylinder, drill bit holding means, a drill bit longitudinally movable therein, a funicular holding member adapted to engage directly the drill bit shank, and means for securing the holding member to the drilling machine.

11. In a hammer drill, the combination with a cylinder having a front head with side rods and cushioning springs, a drill bit adapted to have a longitudinal movement in the front head, a drill bit retaining device comprising a flexible member adapted to engage the drill bit shank and means interposed between the cushioning springs and the cylinder head for yieldably securing the ends of said flexible member.

12. In a hammer drill, the combination with a cylinder drill bit holding means, a drill bit longitudinally movable therein, a flexible holding chain adapted to engage the drill bit shank and prevent the escape of the drill bit holding means, and means for fastening the ends of the holding chain to the drilling machine.

13. In a hammer drill, the combination with a cylinder, a chuck, a drill bit loosely held for longitudinal movement in said chuck, a flexible retaining device comprising a member adapted to be wrapped about the drill bit shank, and means for securing its ends to the drilling machine.

14. In a hammer drill, the combination with a cylinder having drill bit holding means in which the bit is capable of longitudinal movement, a drill bit and a flexible holder having its ends attached to the drilling machine and having its intermediate portion forming a loop adapted to engage the shank of the bit and hold the same against escape.

15. In a hammer drill, the combination with a cylinder, drill-bit holding means, a drill bit longitudinally movable therein and a ligature connecting the drill bit with the drilling machine and having a portion adapted under tension to constrict about the drill bit shank.

16. In a hammer drill, the combination with a cylinder, drill-bit holding means, a drill bit longitudinally movable therein and a ligature connecting the drill bit with the drilling machine and adapted under tension to grip the drill bit shank.

In testimony whereof, I have signed my

name to this specification, in the presence of two subscribing witnesses.
